UNITED STATES PATENT OFFICE.

JOHN C. WILSON, OF BOSTON, MASSACHUSETTS, ASSIGNOR TO THE MUNICIPAL SIGNAL COMPANY, OF PORTLAND, MAINE.

SIGNAL-BOX.

SPECIFICATION forming part of Letters Patent No. 448,399, dated March 17, 1891.

Application filed May 17, 1887. Serial No. 238,459. (No model.)

To all whom it may concern:

Be it known that I, JOHN C. WILSON, of Boston, county of Suffolk, and State of Massachusetts, have invented an Improvement in 5 Signal-Boxes, of which the following description, in connection with the accompanying drawings, is a specification, like letters and figures on the drawings representing like parts.

This invention has for its object to construct 10 a multiple-signal-transmitting apparatus for signal-boxes, it being especially applicable for police-signaling purposes.

In accordance with this invention the signaling-surfaces are made of notched or toothed 15 strips secured to and projecting from a drum in a line parallel with the axis of the drum, and a contact-pen is secured to a rotatable shaft and adapted to sweep over the signaling-surfaces lying or brought into the path of 20 movement of the pen. A suitable motor mechanism is employed for rotating the contact-pen, which is set in operation by a starting-lever. A locking and releasing device is employed for the drum carrying the signaling-surfaces for locking the drum to present any 25 desired signaling-surface to the pen and for releasing the said locking device, permitting the drum to resume its normal position.

Figure 1 shows in front elevation a signal- 30 box having a signal-transmitting mechanism, shown in dotted lines; Fig. 2, a side view of the signal-transmitting mechanism, and Figs. 3 and 4 modifications to be referred to.

The contact-pen *a* is fixed to the outer end 35 of a shaft *a'*, having its bearings in a suitable frame-work secured within the box or case *A*. The shaft *a'* is rotated by a motor mechanism, herein shown as comprising a pinion 2, fixed to the shaft *a'*, and driven by a toothed wheel 40 3, fixed to a shaft 4, upon which shaft is mounted the mainspring and ratchet-clutch mechanism, whereby the said shaft may be turned in one direction to wind the motor and released to return to its normal position to 45 drive the motor. A suitable scape-wheel, as 5, is fixed to the shaft *a'* to regulate the speed of the motor.

The crank-arm 6 is fixed to the winding shaft 4, which arm is connected by a link 7 50 with one end of an actuating-lever 8, pivoted

at 9, the opposite end of the actuating-lever having a finger-piece 10, the shank of which follows in a slot 12, cut in the face-plate of the box. The smooth-face leading-wheel 13 is fixed to the shaft *a'*, upon which bears a 55 pen 14. The drum or cylinder *c* is fixed to a shaft *c'*, to the outer end of which shaft a pointer *p* is secured, so that by turning the pointer the drum will be rotated.

The signaling-surfaces, herein shown as irregular toothed or notched strips *c'*, are fixed to the drum or cylinder *c*, extended lengthwise thereof; but, if desired, the said surfaces may be formed as projections or studs secured to or made integral with the cylinder *c*, as 65 shown in Fig. 3.

The axis of rotation of the cylinder *c* is at right angles with relation to the axis of rotation of the contact-pen, and one or another signaling-surface will be brought into the 70 path of movement of the said pen as the cylinder is revolved.

The face of the box is marked off or graduated to serve as a dial, over which the pointer travels to thus indicate which signal shall 75 be transmitted.

A toothed wheel *i* is fixed to the shaft *c'*, and a latch *i'*, pivoted to the frame-work, is provided at one end with a friction-roller, which enters between the teeth of the wheel 80 *i*, the said latch being normally held in engagement with the wheel by a spring *i*². The latch *i'* is moved to disengage the toothed wheel *i* by a bent rod *i*³, pivoted at *i*⁴, and provided with a hooked end, which bears upon 85 the outer end of the latch.

The toothed wheel 3 of the motor mechanism is provided with a series of pins or studs *n* at equal distances apart, which in the rotation of the said wheel strike the rod *i*³ and 90 depress it, thereby releasing the latch.

The outer or rear end of the shaft *c'* is provided with a weight *w*, so that as soon as the latch releases the drum the weight will return to the same to its normal position.

The studs are arranged upon the face of the wheel 3 to effect the releasing of the latch *i'* just after the signal has been transmitted, so that the drum will be held in fixed position while the signal is being sent, but will be re- 95 100

leased as soon as it has been sent to thereby return the drum and pointer to its normal position.

Some of the features herein shown are substantially such as shown and described by me in other applications filed concurrently with this, Serial Nos. 238,458 and 238,460, and such features I do not herein claim.

While the signal-transmitter shown in Figs. 1, 2, and 3 is adapted for an open circuit, it may and preferably will be modified to be applicable to a closed circuit, which modification I consider comes within the scope of my invention and is illustrated in Fig. 4, the cylinder having at one end a hub on which the pen bears as the cylinder is rotated. The box may also be provided with a suitable door, if desired.

I claim—

1. In a signal-box, the contact-pen and motor mechanism for rotating it and the signal-drum and means for rotating it, combined with an engaging latch for the drum and means controlled by the motor for effecting the movement of the latch to release the drum, substantially as described.

2. In a signal-box, the contact-pen, a motor mechanism for rotating it, the signal-drum and means for rotating it, the toothed wheel i , latch i' , rod i'' , and the wheel 3, having the studs n thereon, substantially as described.

3. In a signal-box, a multiple-signal transmitter comprising the contact-pen, a revolute shaft a' , to which it is fixed, a cylinder with parallel sides having thereon longitudinally-arranged signaling-surfaces, the axis of rotation of which cylinder is at right angles to the axis of rotation of the shaft a' , the pen being arranged tangentially to the cylinder, and means for revolving said cylinder to bring one or another signaling-surface into the plane of rotation of the contact-pen, substantially as described.

In testimony whereof I have signed my name to this specification in the presence of two subscribing witnesses.

JOHN C. WILSON.
